Franklin H. Strong

Attorney

UNITED STATES PATENT OFFICE.

WILLIAM HENRY ERNST, OF BLOOMINGTON, INDIANA.

MECHANICAL ARM.

SPECIFICATION forming part of Letters Patent No. 787,839, dated April 18, 1905.

Application filed November 17, 1904. Serial No. 233,207.

To all whom it may concern:

Be it known that I, WILLIAM HENRY ERNST, a citizen of the United States, residing at Bloomington, in the county of Monroe and State of Indiana, have invented certain new and useful Improvements in Mechanical Arms; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to new and useful improvements in mechanical arms or devices for use in connection with wiring of various kinds; and it consists in a cross-arm having means for holding the same securely to the 20 top of a telephone or other pole and having notches to receive the series of line-wires for the purpose of holding the same while an old arm is being removed and a new one replaced, means being provided for holding straight 25 line-wires or wires at a curve or at an angle.

The invention consists in various details of construction and in combinations and arrangements of parts, which will be hereinafter fully described, and then specifically defined in the 30 appended claims.

My invention is illustrated in the accompanying drawings, which, with the letters of reference marked thereon, form a part of this application, and in which—

35 Figure 1 is a view showing the application of my apparatus to a pole and illustrating the manner in which the line-wires are held by the cross-arm of the apparatus while an old arm is being replaced by a new one. Fig. 2 40 is a view showing the manner of application of the apparatus for holding line-wires at a curve or at an angle, and Fig. 3 is an enlarged perspective view of the mechanical arm.

Reference now being had to the details of 45 the drawings by letter, A designates a cross-arm having series of slots E in the upper edge thereof and slots F in the lower edge for the reception of line-wires, which are temporarily held while the cross-arm of a pole is being 50 replaced. Securely bolted or otherwise fas-

tened to said cross-arm A is a V-shaped member D, having a sharp edge D', adapted to cut into and be securely held upon the top of a pole, as illustrated in Fig. 1, of the drawings. Said V-shaped member has right-angled portions, which bring the sharp edges thereof in a plane parallel to the vertical faces of the cross-arm in order to allow a sufficient space to intervene between the cross-arm and the part which is made to engage the top of the pole. Angled arms G are bolted or otherwise secured to said V-shaped member and are positioned one opposite the other and are designed to engage over a cross-arm of a pole immediately above the one which is to be replaced. In adapting the apparatus for use in connection with curves or angles in line-wires I provide a strap K, having loops K' at its ends, which are designed to engage the hooks N in the ends of said cross-piece. Said strap may be held from sagging from the cross-piece intermediate its ends by means of the straps O, which pass about the cross-arm and hold the strap K, as shown in the drawings. Secured to the strap K are 75 series of stirrups Q, to which snap-hooks J are connected, and secured to said snap-hooks J are series of straps L, said straps being of different lengths and carrying hooks J' at their lower ends. By the provision of said 80 straps of different lengths and having snap-hooks, as shown, means is provided for engagement with line-wires at curves or angles, as will be readily understood and as is illustrated in the accompanying drawings. 85 In applying my apparatus to poles the V-shaped sharpened edge of said member is driven into the top of the pole, which will insure the cross-piece being securely held while a cross-arm is being replaced and enables the 90 operator to remove the wires from the cross-arm upon the pole and allow them to rest in the notches upon the upper edge of the apparatus, and the several wires are thus kept clear of one another, while the arms of the operator are free and at liberty for use in removing the old cross-arm and attaching another, after which the wires may be removed from the apparatus and fastened to the insulators 95 of the new cross-arm, thus dispensing with 100

the services of an extra person commonly employed to assist in replacing cross-arms upon poles. In utilizing the apparatus at curves or angles the strap K is brought into play 5 and the various line-wires are engaged by the different-length straps having snap-hooks thereon, as will be readily understood.

While I have shown a particular construction of apparatus illustrating my invention, 10 it will be understood that I may vary the same as to details, if desired, without in any way departing from the spirit of the invention.

Having thus fully described my invention, 15 what I claim as new, and desire to secure by Letters Patent, is—

1. A mechanical arm for use in connection with poles for replacing cross-arms, comprising a bar having slots in the edge thereof designed to temporarily hold the line-wires, and 20 a metallic bracket member having a sharp edge adapted to cut into the top of a pole, as set forth.

2. A mechanical arm for use in connection with poles for replacing cross-arms, comprising a bar having slots in the edge thereof designed to temporarily hold the line-wires, a metallic bracket member having a sharp edge 25 adapted to cut into the top of a pole, angled arms secured to said bracket member adapted for engagement with the cross-piece mounted upon a pole, as set forth.

3. A mechanical arm for use in connection with poles for replacing cross-arms, comprising a bar having slots in the edge thereof designed to temporarily hold the line-wires, a 30

metallic bracket member having a cutting edge in a plane parallel with the plane of the vertical faces of said bar and designed to cut into the top of a pole, and arms projecting 40 from said bracket member and adapted for engagement with the cross-piece of a pole, as set forth.

4. A mechanical arm for use in connection with poles for replacing cross-arms, comprising 45 a bar having slots in the edge thereof designed to temporarily hold the line-wires, a metallic bracket member having a sharp edge adapted to cut into the top of a pole, a strap secured to the ends of said bar, stirrups secured to said strap and a series of straps of different lengths and provided with snap-hooks at their ends, designed to engage said stirrups, as set forth.

5. A mechanical arm for use in connection 50 with poles for replacing cross-arms, comprising a bar having slots in the edge thereof designed to temporarily hold the line-wires, and a metallic bracket member having a sharp edge adapted to cut into the top of a pole, 55 hooks secured to the ends of said bar, a strap having bails secured thereto, the end bails of said strap adapted for engagement with said hooks, a series of straps of different lengths, and snap-hooks at the ends thereof for engagement with said bails, as set forth.

In testimony whereof I hereunto affix my signature in presence of two witnesses.

WILLIAM HENRY ERNST.
